[57] **CLAIM**

The ornamental design for a rotatable gaming wheel, as shown and described.

DESCRIPTION

FIG. 1 is a top plan view of a rotatable gaming wheel showing my new design;

FIG. 2 is a side elevational view thereof, the opposite side being a mirror image thereof;

FIG. 3 is a bottom plan view thereof; and,

FIG. 4 is a cross-sectional side elevational view taken along a central diameter of FIG. 1.

FIG. 1

FIG. 2

FIG. 3

FIG. 4
